UNITED STATES PATENT OFFICE.

WILLIAM E. BLAIR, OF BUFFALO, NEW YORK, ASSIGNOR TO BUFFALO GASOLENE MOTOR COMPANY, OF BUFFALO, NEW YORK.

PROPELLER-ADJUSTING DEVICE.

No. 897,341.

Specification of Letters Patent.

Patented Sept. 1, 1908.

Application filed March 16, 1907. Serial No. 362,680.

To all whom it may concern:

Be it known that I, WILLIAM E. BLAIR, a citizen of the United States, residing at Buffalo, in the county of Erie and State of New York, have invented a new and useful Improvement in Propeller-Adjusting Devices, of which the following is a specification.

This invention relates to a propeller adjusting device for boat motors such as that shown and described in Letters Patent No. 849,719, dated April 9, 1907.

The object of this invention is to improve the construction of the propeller adjusting device shown in the above mentioned application so as to permit of operating the same more easily.

In the accompanying drawings consisting of 2 sheets: Figure 1 is a side elevation partly in section, of my improved adjusting device applied to the reversible propeller of a marine gas engine. Fig. 2 is a top plan view thereof. Fig. 3 is a fragmentary vertical section, on an enlarged scale, of the adjusting device arranged in a position reverse of that shown in Figs. 1 and 2. Fig. 4 is a top plan view of the same. Fig. 5 is a fragmentary horizontal section taken in line 5—5, Fig. 3.

Similar letters of reference indicate corresponding parts throughout the several views.

A represents an upright marine motor or gas engine which may be of any suitable construction and provided with a longitudinal horizontal driving shaft *a* in its lower part.

B represents the hollow hub of the propeller which is connected with the rear end of a hollow propeller shaft *b*. The rear end of the engine shaft and the front end of the propeller shaft are connected by a hollow coupling *C*.

D represents the propeller blades which are journaled on the hub and provided within the latter with crank pins or wrists *d* which are engaged with a longitudinal movable shifting head *E*.

F represents a shifting sleeve which is movable lengthwise on the engine shaft and operatively connected with the shifting head *E* by means of a cross head *f* movable axially in the hollow coupling *C*, two shifting rods *g*, *g* connecting the ends of the cross head with the shifting sleeve and passing through the coupling *C* on opposite sides of the engine shaft and a central shifting rod *e* connecting the central part of the cross head and the

shifting head and extending through the hollow propeller shaft, these parts being all of well known construction.

H represents an upright adjusting shaft journaled at its lower end in a bearing *h* formed on a bracket *h*¹ which is secured to the lower part of the engine frame and operatively connected with the shifting sleeve *F* by means of a shifting ring *I* surrounding the latter between two shoulders thereon and a rock arm *J* secured to the lower part of the adjusting shaft and operatively connected with the shifting ring. Upon rocking this adjusting shaft toward either side of its central position the propeller blades are turned in one direction or the other and cause the boat to move either forward or backward but when the adjusting shaft is in its central position, the propeller blades are so turned that they are neutral and have no propelling effect.

*h*¹ represents a bearing in which the adjusting shaft is journaled near its upper end and which is formed on the upper end of an inclined bracket *h*² secured at its lower end to the adjacent upper part of the engine frame. At its upper end the upper bearing *h*² is provided with an annular flange *M* which contains a plurality of screw threaded openings *m* arranged equi-distant and circumferentially around the adjusting shaft.

N represents a supporting head or plate which is mounted on the upper end of the bracket *h*² so as to be capable of circumferential adjustment around the adjusting shaft. For this purpose the head *N* is provided with an opening *n* which receives the upper end of the shaft *H* and a plurality of openings *n*¹ which are adapted to receive bolts or screws *m*¹ entering the openings *m* of the flange *M*. These screws *m*¹ and openings *m*, *n*¹ are preferably arranged on the four quarters of a circle so that the head and parts mounted thereon may be shifted into four different positions relatively to the adjusting shaft to suit different conditions, but if desired these screw openings may be of a different number and spacing.

O represents a vertical counter shaft which is journaled at its lower end in a bearing *o* on one side of said supporting head parallel with the adjusting shaft. Above its bearing the counter shaft is provided with a small gear segment *o*¹ which is preferably formed integrally with the counter shaft. The counter

shaft is held against vertical movement in its bearing by the gear segment o^1 engaging with the upper end of the bearing o and a screw nut o^2 applied to the lower end of said shaft and engaging with the lower end of its bearing, as shown in Figs. 1 and 3.

P represents a large gear segment which is secured to the adjusting shaft above the supporting head and meshes with the small gear segment o^1 . The large gear segment is capable of being adjusted circumferentially on the adjusting shaft to suit the position of the counter shaft relative to the adjusting shaft, the adjustable connection for this purpose consisting preferably in making that portion of the adjusting shaft above the head square or of other flat sided form, as shown at p , and engaging the same with a correspondingly shaped opening in the hub of the large segment, and a screw nut p^1 applied to the upper end of the adjusting shaft and engaging with the upper end of the hub of the large segment.

Q represents a hand lever which is secured to the upper end of the counter shaft and preferably projects toward the adjusting shaft over the top of the supporting head. The hand lever is connected with the counter shaft by providing its hub with a square or flat-sided opening which receives a correspondingly shaped part q of the counter shaft above its gear segment and a clamping screw nut q^1 applied to the upper end of the counter-shaft and engaging with the upper end of the hub of the hand lever, as shown in Fig. 3.

R represents a locking segment arranged between the under side of the hand lever and the upper side of the supporting head and on that side of the adjusting shaft opposite the counter shaft. As shown in Fig. 3, the locking segment is formed integrally with the supporting head but if desired the same may be made separate and secured thereto.

S represents a locking pawl or dog which is guided in a way s on the underside of the hand lever and yieldingly held in engagement with the teeth of the locking segment by a spring t .

u is a locking lever pivoted on the underside of the hand lever and connected by a rod v with the locking pawl.

Upon releasing the locking pawl from the locking segment the hand lever may be turned horizontally which movement is transmitted at a reduced speed from the counter shaft to the adjusting shaft by the intermeshing large and small gear segments. By this means an increased leverage is obtained which enables the propeller blades to be adjusted more easily than is possible when the hand lever is connected directly with the adjusting shaft.

When it is desired to change the position of the hand lever relative to the adjusting

shaft so that it projects either forward, backward or laterally therefrom or to suit the location of the motor on the boat, the structure of the boat or other conditions, this can be done by disconnecting the large gear segment 70 from the adjusting shaft and the supporting head from the bracket and then re-connecting said parts after the hand lever, the supporting head and parts mounted thereon have been shifted into the required position. 75

I claim as my invention:

1. A propeller adjusting device comprising a main driving shaft, propeller blades adjustably supported on said main shaft, a shifting rod movable lengthwise of the main 80 shaft and operatively connected with the propeller blades, a main adjusting shaft arranged at an angle to the main driving shaft and adjusting rod and operatively connected with said rod, a counter shaft arranged parallel with the main adjusting shaft, a large gear secured to the main adjusting shaft, a small gear secured to the counter shaft and meshing with the large gear, and a hand lever connected with the counter shaft, substantially as set forth. 90

2. A propeller adjusting device comprising an adjusting shaft adapted to be operatively connected with a propeller, a counter shaft, intermeshing gears secured to said adjusting 95 and counter shafts, respectively, a hand lever connected with said counter shaft, and a supporting head which is adjustable circumferentially relatively to said adjusting shaft and which is provided with a bearing in which 100 said counter shaft is journaled, substantially as set forth.

3. A propeller adjusting device comprising an adjusting shaft adapted to be operatively connected with a propeller, a counter shaft, 105 intermeshing gears secured to said adjusting and counter shafts, respectively, a hand lever connected with said counter shaft, a bracket having a bearing in which said adjusting shaft is journaled, and a supporting head secured to said bracket so as to be capable of circumferential adjustment around said adjusting shaft and provided with a bearing in which 110 said counter shaft is journaled, substantially as set forth. 115

4. A propeller adjusting device comprising an adjusting shaft adapted to be operatively connected with a propeller, a counter shaft, intermeshing gears secured to said adjusting 120 and counter shafts, respectively, a hand lever connected with said counter shaft, a bracket having a bearing in which said adjusting shaft is journaled, a supporting head secured to said bracket so as to be capable of circumferential adjustment around said adjusting 125 shaft, a bearing which is arranged on said head on one side of said adjusting shaft and in which said counter shaft is journaled, a locking segment arranged on said head on the opposite side of said adjusting shaft, and a 130

locking pawl mounted on said hand lever and adapted to engage said locking segment, substantially as set forth.

5. A propeller adjusting device comprising an upright adjusting shaft, a counter shaft, a small gear segment arranged on the central part of the counter shaft, a large gear segment meshing with the small gear segment and adjustably secured to the upper end 10 of said adjusting shaft, a bracket having a bearing in which the adjusting shaft is journaled, a supporting head adjustably secured to said bracket and having a bearing in which the lower end of the counter shaft is

journaled, a screw nut applied to the lower 15 end of the counter shaft and engaging with the lower end of its bearing, a hand lever connected with the counter shaft above its gear segment, and a screw nut applied to the upper end of the counter shaft and engaging 20 with the upper end of the hub of the hand lever, substantially as set forth.

Witness my hand this 12th day of March, 1907.

WILLIAM E. BLAIR.
